UNITED STATES PATENT OFFICE.

WILLIAM L. CALDWELL, OF CANTON, OHIO, ASSIGNOR, BY MESNE ASSIGNMENTS, TO UNITED ALLOY STEEL CORPORATION, OF CANTON, OHIO, A CORPORATION OF NEW YORK.

METALLIC FLUME.

Application filed November 17, 1919. Serial No. 338,698.

To all whom it may concern:

Be it known that I, WILLIAM L. CALDWELL, a citizen of the United States, residing at Canton, in the county of Stark and State of Ohio, have invented a new and useful Metallic Flume, of which the following is a specification.

The invention relates to improvement in metallic flumes, in which a thin metallic trough is used for conveying water for power, irrigation or analogous purposes, the trough being formed of successive sections of proper curvature and joined together to form a continuous channel. In order to facilitate the assembling of flumes of this character the joints between the several sections should be made with a minimum of separable parts and without rivets or bolts, and to provide a water tight joint between the several sections, means should be provided for clamping the overlapped ends of the sections tightly together. The joints should further add a certain amount of circumferential stiffness to the thin shell of the flume sections and should be made water tight without the use of solder or the like.

The objects of the invention are to provide a flume in which the joints between the sections are made with a minimum of separable parts, the joints being made water tight without the use of solder, bolts, rivets or other supplemental means; to provide a joint between the flume sections in which no inner pressure bar is necessary; to provide a joint between the flume sections having interior means for forcing the parts into position, thus aiding materially in assembling the flume and preventing displacement of the parts by strains placed thereon; to provide a flume having an integral pressure member; and to generally improve and simplify the construction of sheet metal flumes.

These objects together with supplemental objects are attained by providing a sheet metal flume made up of semi-circular sections, each section being provided at one end with an integral reinforced pressure portion, the other end of each section being preferably provided with a peripheral recess, the reinforced end of one section being placed within the recessed end of the next adjacent section and held in engagement therewith by

providing a hanger and a clamping bar which is connected to the hanger and arranged to draw the edges of the inner section against the hanger and to clamp the overlapped end against the innerlapped end, means being provided upon the hanger for forcing the pressure member upon the inner section into tight engagement with the recessed portion of the outer section.

The invention thus set forth in general terms is illustrated in the accompanying drawings forming part hereof, in which—

Figure 1 is a perspective view of portions of two sections of flume showing the joint.

Fig. 2 is a plan view of portions of several sections of flume showing the joints between the sections.

Fig. 3 is a transverse sectional view through the joint of the flume sections.

Fig. 4 is an enlarged sectional view showing the function of the locking tongues.

Fig. 5 is a view similar to Fig. 2, of a slightly modified form of flume.

A practical embodiment of the invention is disclosed in the accompanying drawings, forming a part of this specification in which similar numerals of reference indicate corresponding parts throughout the several views.

Quite often conditions require that the flumes be constructed of considerable length and that they be supported in places at an appreciable distance above the ground, it being frequently necessary to erect the flumes at the proper level and inclination in order that water may be carried over elevations and across valleys. For this purpose it is necessary to erect a trestle or other suitable frame work of varying height in order that the proper level and inclination of the flume may be maintained, the flume being supported throughout its length by means of suitable hangers 1 which are carried by the trestle or frame work.

The flume sections 2 are preferably formed of sheet metal and are semi-circular in cross section as indicated in the drawings, these sections being of suitable length to permit of their being easily handled and assembled. Each section is provided at one end with a folded back reinforcing portion 3, which constitutes an integral pressure

bar, the other end of each section being preferably provided with the peripheral recess 4 arranged to receive the reinforced end of the next adjacent section. In order that the 5 bottom of the trough or the surface upon which the water flows is smooth, thereby offering the least resistance to the flow of water, each section is preferably off-set as shown at 5 bringing the inner surface of the 10 reinforced portion 3 into the same plane with the interior of the flume.

The integral pressure member 3 is arranged to be placed within the recessed end 4 of the next adjacent section and the curved 15 clamping bar 6 is arranged to be placed around the outer side of the overlapped ends of the flume sections. This clamping bar is of a size and shape to correspond substantially with the curvature of the exterior 20 of the recessed portion 4 of the flume section around which the bar is arranged to be located and is provided at each end with a reduced threaded portion 7.

The hanger 1 is preferably formed of 25 channel iron as illustrated in the drawings and the flume sections are clamped thereto by means of the threaded extremities 7 of the clamping bar, which extend through suitable apertures in the hanger, nuts 8 being provided thereon for drawing the flume sections toward the hanger and clamping the overlapped end between the clamping bar and the integral pressure member upon the innerlapped end.

35 The hanger is provided with means acting against the ends of the integral pressure portion on the innerlapped end and forcing them directly outward against the side or end portions of the overlapped end.

40 Preferred means for the purpose are the flexible locking lugs 9 which may be tongues stamped from the web plate of the hanger, whence they extend downward and inwardly at such an angle that their ends will stand 45 fully inside of the pressure portion of the innerlapped end when the parts are assembled as shown in full lines in Fig. 4.

50 After assembling the parts thus described in detail the nuts 8 are then tightened on the clamping bolts so as to draw the clamping bar snugly against the overlapped end, clamping the overlapped end against the reinforced pressure portion of the innerlapped end with the ends thereof in abutment with the under side of the hanger. The locking lugs are then driven upward by means of a hammer or other suitable tool until their free ends wedge against the inner side of the integral pressure portion 55 near the ends thereof, as shown by dotted lines in Fig. 4; and force them directly outward against the side portions of the overlapped end.

60 The bolts are then further tightened so as 65 to clamp the overlapped end of the one

flume section between the clamping bar and the innerlapped end of the other flume section, such clamping action being accomplished by the strength of the clamping bar 70 operating against the integral pressure portion 3 as an abutment.

There is no clamping action of the bolts at the sides of the flume adjacent to the hanger because the pull of the bolts on the clamping bar is substantially parallel with the 75 end portions of the integral pressure member; but the action of the locking lugs positively presses the ends of the integral pressure portion outward so as to clamp the edge portions of the innerlapped end of the one flume section against the abutment formed by the end portions of the clamping bar; which are stopped against lateral movement by the clamping bolts.

80 Thus the overlapped ends of the flume sections are clamped together at the sides as well as at the bottom of the flume and it is evident that when the lugs 9 have been driven upward to effect the clamping action thus described, they will be locked in such position by their wedge action against the integral pressure portion as well as by a biting into the same.

85 The structure is stiffened circumferentially by means of the folded integral pressure portion 3 as well as by the clamping bar, the joint between the sections being braced by reason of the coaction between the integral pressure portion and the clamping bar, no inner pressure bar being necessary with this construction as the folded portion 3 acts as an integral pressure bar.

90 For the purpose of further assuring a water tight joint between the sections of the flume a mastic may be applied to the joints between the sections. This mastic may be what is known to the trade as "gilsonite," and when placed in the joints of the flume sections forms a water tight seal 95 between the sections obviating any leakage 100 of the flow of water through the flume at the joints.

105 Reference is made to my copending applications, Serial No. 338,695, Serial No. 338,696 and Serial No. 338,697, which contain claims to subject-matter which is related to that which is set forth in the claims 110 made in this application, as follows.

I claim:

115 1. A metallic flume including adjoining sections having overlapped ends, a transverse hanger adjacent to the edges of the overlapped ends, means connected with the hanger for clamping the overlapped ends 120 against the innerlapped end, there being outwardly extending tongues struck downward from the hanger inside the edges of the innerlapped end and wedged upward against the same to press them outward against the 125 edges of the overlapped end.

2. A metallic flume including adjoining sections having overlapped ends, a transverse hanger adjacent to the edges of the overlapped ends, the innerlapped end being off-set outward and folded inward upon its off-set portion to form an integral pressure member for abutting the hanger at the ends

of said member, and the outerlapped end being off-set outward to form a seat for the innerlapped end, and means for clamping ¹⁰ the outerlapped end against the innerlapped end.

WILLIAM L. CALDWELL.
